DESIGN FOR A SOCKET SCREW DRIVER

John Magnus, Jr., Hazleton, Pa.

Application March 19, 1947, Serial No. 137,746

Term of patent 7 years

(Cl. D93—4)

To all whom it may concern:

Be it known that I, John Magnus, Jr., a citizen of the United States, residing at Hazleton, in the county of Luzerne, in the State of Pennsylvania, have invented a new, original, and ornamental Design for a Socket Screw Driver, of which the following is a specification, reference being had to the accompanying drawing, forming a part thereof.

Fig. 1 is a top plan view of a socket screw driver, showing my design;

Fig. 2 is a side elevational view;

Fig. 3 is a side elevational view taken at right angle to Fig. 2; and

Fig. 4 is a bottom plan view.

I claim:

The ornamental design for a socket screw driver, as shown.

JOHN MAGNUS, JR.
